UNITED STATES PATENT OFFICE

2,584,869

COMBINATION UNIT SHOWCASE

Robert Jay Gunder, Lancaster, Pa., assignor to
Hamilton Watch Company, Lancaster, Pa.

Application June 6, 1946, Serial No. 674,690

1 Claim. (Cl. 312—114)

1

This invention relates to show-cases and more particularly that type of show-case which is designed for jewelery stores.

The object of the invention is to provide show-case units which may be connected in any desired numbers by rails supporting other show-case units, the connecting and supported units being bodily removable and interchangeable.

A further object of the present invention is to provide a show-case made up of a number of individual units which will fit to almost any conceivable space and which will provide the utmost in display and selling convenience both for the customer and the seller.

A still further object of the present invention is to provide a show-case unit having self-carried concealed illumination so constructed as to be readily available for repairs or replacements of the lighting units.

A still further object of the invention is to provide a lighting unit which may be easily removed for replacement of bulbs and which has interchangeable panels so that transparent, translucent or opaque panels may be used at will.

It is a still further object of the present invention to provide standard units, which are connected by rails running between the units and display tables formed with individual removable trays for merchandise which are removably carried on the rails and which may be removed each evening for storage in a safe place.

With the foregoing and other objects in view, the invention resides in the novel arrangement and combination of parts and in the details of construction hereinafter described and claimed, it being understood that changes in the precise embodiment of the invention herein described may be made within the scope of what is claimed without departing from the spirit of the invention.

The invention is shown in the accompanying drawings in which:

Figure 1 is a front perspective view of the show-case showing three of the standard units connected by different types of table cases.

Figure 2 is a view of one of the standards showing the table case in broken perspective.

Figure 3 is a back view of the unit shown in Figure 2.

Figure 4 is a detail view showing the connection of the rails to the side of the standard units.

Figure 5 is a view of the removable lighting unit showing an opaque panel on one side and a translucent panel on the other.

2

Referring particularly to Figure 1, a standard unit 1 having a reduced base portion 2, front 3, sides 4, a display floor 5 and a glass front and top 6.

5 These standards are connected by table cases 7 or 8 which may be of any desired length or depth and are here shown of two standard depths, the shallow table case 7 and the deeper table case 8. The table cases 7 and 8 to be described in 10 detail hereinafter are removably set on rails 9 and may be lifted therefrom as a unit and removed to a safe place for night storage.

It is the custom of jewelers to arrange their merchandise in trays and to remove these trays 15 containing the valuable items from the showcases each evening and store the trays or their contents in the safe for the night. It is possible with the specially designed table cases here shown to remove the entire case which may be 20 made of light plywood or plastic and to store the entire case in the safe for any desired period. This would save the jeweler many hours of work each morning and evening normally required to untrim and return the cases.

25 Referring to Figures 2 and 3, the standards 1 are formed in a lower section with shelves 10 and sliding doors 11 for the storage of any merchandise. A bottom pivoted door 12 gives access to the display floor 5 while removable units 13 30 provide lighting for the display floor and the table cases, which units will be described hereafter.

Attached to the sides 4 of the standard units 1 are rails 9 by means of screws 14. These rails 35 may be of any light metal and are of T-shape formation in cross-section to receive and more or less rigidly support the table cases 7 or 8. The trays 7 which are formed in the bottom board 15 with T-shaped slots to receive the rails 9 house removable trays 16 in which other trays carrying the merchandise for sale on velvet cloths or pads may be carried. This makes the contents easily accessible and convenient for the jeweler to remove any desired item for close inspection by the customer.

40 Referring particularly to Figure 5, the unit 13 formed with a bottom base 17, side frames 18 and end panels one of which is here shown 19. The side frames 18 are open at 20 to allow the panels 50 21 or 22 to be slid into the frames so that any desired panel may be used, for instance panel 21 is here shown as an opaque plywood panel while panel 22 is a piece of translucent glass. It would of course be easy to provide transparent glass or 55 glass of any desired color. Mounted on the end

panels 19 are supports 23 for cold light tubes 24 which supply light through the panels 22 as desired. This unit may be removed completely from the standard unit 1 and the panels 21 or 22 interchanged at will. It is also easy to replace useless tubes by removing one of the panels through the open slot 20.

It is thus seen that a jeweler is provided with display cases having infinite variation, the standard units 1 may be grouped together or they may be separated by any length of the table cases. An attractive and efficient show-case is thus provided for use with any jewelry store whether it be large or small and whether its needs for show-cases be few or great.

What is claimed is:

A composite show-case and display counter comprising a plurality of standard show-case units formed with a transparent top, front and back and arranged at spaced intervals, pairs of rails connecting and separating said show-case units at standard distances and table cases having a transparent top having bottoms formed

with grooves receiving said rails so that said table cases are firmly yet removably supported between said standard units and at substantially table height.
